UNITED STATES PATENT OFFICE

2,529,714

VENETIAN BLIND

Walter Turkowski, Hollywood, Ill.

Application May 26, 1947, Serial No. 750,555

8 Claims. (Cl. 160—166)

1

My invention relates to adjustable window blinds of the type commonly known as Venetian blinds.

My invention relates more particularly to Venetian blinds of the type that are adapted to be suspended vertically rather than the usual horizontal position.

The principal object of the present invention is to provide adjustable Venetian blinds embodying a plurality of normally vertically disposed slats or shutters mounted to turn about their longitudinal axis to various positions of adjustment for controlling the amount and direction of light and air passing through a window.

A further object of the present invention is to provide window blinds of the above type in which the shutters or slats are also mounted to swing laterally so that they may be adjustably gathered at their lower ends without disturbing their positions at their upper ends.

A further object of the invention is to provide an improved construction of this type of Venetian blind whereby the adjustable gathering at the lower end may be controlled by a brace or rod support member that may be swung to a tilted or to a horizontal position. In its horizontal position the slats will be hung vertically.

A further object of the invention is to provide a Venetian blind unit which may include two sets of vertically hung slats, the mechanism for tilting the slats or gathering the lower ends, the entire unit being adapted to be sufficiently light and sturdy so that it can be hung upon suitable brackets in the window sill.

A further object of the invention is to provide a mechanism for swinging the lower ends of the slats to the side which mechanism may be in the form of a bar fastened through a plurality of slats and having means on the bar for holding the slats comparatively rigid either in a vertical position or with the slats slopingly directed to the sides, the same mechanism permitting partial rotation of the slats so that the same may be turned even though the lower ends are gathered to one side.

A further object of the invention is to provide a mechanism of the type described for swinging the slats to a tilted position so arranged that half of the slats may be controlled by one mechanism and half by the other, whereby when the lower end of the slats are gathered together the Venetian blinds will have the appearance of drapes on the window.

A further object of the invention is to provide a Venetian blind of the type described that

2

is easily and simply constructed, yet sufficiently rigid and sturdy so that it can be given long and hard usage without becoming broken or out of order.

Other objects and advantages will be more apparent from the following description wherein reference is had to the accompanying two sheets of drawings, upon which:

Fig. 1 is a front elevational view showing the assembly of a complete Venetian blind unit capable of being hung in a window frame, with parts shown in section to more clearly show other parts;

Fig. 2 is a plan view of the same;

Fig. 3 is a fragmentary side elevational view of the side rod members upon which the slat gathering blade is mounted;

Fig. 4 is a fragmentary side elevational view of the same;

Fig. 5 is a fragmentary sectional view showing one of the slats with the opening through which the slat gathering blade passes;

Fig. 6 is a cross-sectional view of the same taken generally on the line 6—6 of Fig. 5;

Fig. 7 is a generally diagrammatic view showing a different type of slat gathering blade in connection with an assembly of vertical slats;

Fig. 8 is a fragmentary view of one of the slats and the blade and;

Fig. 9 is a cross-sectional view taken on the line 9—9 of Fig. 8.

In the embodiment of the invention which I have chosen to illustrate, I have provided a frame adapted to be suspended in the window frame on suitable brackets. This may include the end block members 10 and 12 connected together by suitable cross-frame members 14 and 16. I provide a pair of L-shaped brackets 18 upon the sides of the end frame members 10 and 12, the brackets 18 being provided with ledges so they can rest upon a bracket in the window frame, which will position the entire Venetian blind unit so there will be no back and forth movement of the same, yet the entire unit can be lifted off the brackets and handled as a unit when it is desired to wash the windows or in other ways have free access to the window frame.

The rectangular frame which I have provided may have a cross-bar 20 which extends from the member 10 to the member 12 and is rigidly secured to the same. The bar 20 may have a plurality of pin members 22 secured to the same and extending downwardly therefrom to support the U-shaped brackets 24. Each of the brackets 24 is adapted to carry a slat 26 hung therein by

means of a metal clip member that passes through an opening in the slat and through suitable openings in the brackets 24. The slats 26 are arcuate, as shown, and provided with a medial ridge 30 so that when they are pulled to the side, instead of flexing they will maintain rigidity.

Each of the brackets 24 is connected by a suitable pivot to an operating bar 36 which extends throughout the length of the unit and is connected to all of the brackets 24 in the unit. At an intermediate point the operating bar 36 is connected by a bolt member 38 to one end of a lever 40 pivotally mounted upon the cross-bar 28. The lever 40 may carry hooks 42 to which both ends of operating cords 44 and 46 are connected. Thus when either the cord 44 or the cord 46 is pulled, it will swing the operating bar 36 either to the right or to the left to turn the brackets 24, and in this manner the individual slats will be turned to the right or to the left, depending upon which cord is pulled. The cords 44 and 46 may extend from the unit 42 over a pair of pulleys 48 and 50 mounted in suitable brackets on the end frame members 10 and 12.

The mechanism for gathering back the slats may include a pair of rod members 54 and 56 each of which carries a block 58 at its lower end. The block 58 may be formed with a slot 60 within which the blade 62 is positioned, being mounted upon the shaft 64 at the end of an operating handle 66. For holding the blade in either a raised or a horizontal position I provide openings 68 and 70 therein and a spring pressed ball member 72 mounted in the block 58 and adapted to yieldingly hold the blade 62 in either position mentioned.

The blade 62 may be formed with a plurality of notches, so that in the normal position of the slats they will be rigidly held against back and forth swaying, the blade 62 passing through elongated openings 64 in each of the slats 26. The elongated openings 64 are of a sufficient width so that the slats may be turned, as shown in dotted line in Fig. 6, and yet be controlled as to their back and forth swaying when in vertical position.

When it is desired to gather the lower ends of the slats together to give a draped appearance to the unit, the blade 62 is raised passing upwardly in the elongated slots 64 and locked in the uppermost position by means of the spring pressed ball 72 as shown in Fig. 3. In this position the notches 62-A of the blade 62 are again capable of holding the slats rigid in a slanting position, yet permit the partial rotation of the slats whenever the ropes 44 or 46 are pulled.

From the above and foregoing description it will be clear to those skilled in the art that I have provided a vertically hung Venetian blind unit that is easily and simply assembled and one that is easily and simply operated to turn the individual slats in unison when the cords 44 and 46 are pulled down. When it is desired to gather the lower ends of the slats to one side this is done by raising the operating blade 62, as shown in dotted lines in Fig. 2, and the slats are held in this position until the blade is lowered.

In the embodiment of the invention shown in Figs. 7, 8 and 9, I have shown a comparatively narrower slot 64—a in the slat 26—a, the bottom portion of the slot being widened as shown at 65, so that when the slats are suspended in a vertical position they may be swung about at right angles to close or open the same.

With this construction I provide a slat gathering blade 62—a generally formed with the inclined edges 63 as shown, so that in the normal vertical hanging position a slat 26—a will rest in one of the corners of the inclined edges 63. With this construction the slat gathering blade 62—a need only be moved through a comparatively small angle to gather the lower edges of the slats together, as shown in Fig. 7.

10 The general construction of the Venetian blind unit, with the exception of the parts shown in Figs. 3 to 9 of the drawings, may be similar to that shown in my co-pending application—Serial No. 684,102 filed July 17, 1946, now abandoned. 15 The specific novelty of the present construction resides in the mechanism for gathering the slats at their lower ends and for holding the same against back and forth movement when they are vertically suspended.

20 While I have illustrated and described a specific embodiment of the invention and modifications of the same, it will be apparent to those skilled in the art that changes and modifications may be made in the exact details shown and I 25 do not wish to be limited in any particular; rather what I desire to secure and protect by Letters Patent of the United States is:

1. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position.

30 2. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position.

35 40 45

2. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position, said means including toothed blade members extended through slots in said slats.

50 3. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position, said means including toothed blade members extended through slots in said slats, said blade members pivotally mounted and capable of being swung upwardly to gather the lower ends of said slats together to effect a drape appearance.

55 60 65 70 75 80 85 90 95

3. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position, said means including toothed blade members extended through slots

in said slats, said blade members pivotally mounted and capable of being swung upwardly to gather the lower ends of said slats together to effect a drape appearance, and means associated with said blade members for fixedly holding the same horizontal or at an angle.

5. The combination with a blind consisting of a plurality of vertically suspended slats having means for turning adjustment about their lateral axis of a frame in which said blind is mounted at its upper end, said frame including an end block member, a rod member extending from said block member, and means extending therefrom for rigidly holding said slats in vertical position.

6. The combination with a blind consisting of a plurality of vertically suspended slats having means for turning adjustment about their lateral axis of a frame in which said blind is mounted at its upper end, said frame including an end block member, a rod member extending from said block member, and means extending therefrom for rigidly holding said slats in vertical position, said means including a toothed blade pivotally mounted at the end of said rod member and positioned through slots in said slats.

7. The combination with a blind consisting of a plurality of vertically suspended slats having means for turning adjustment about their lateral axis of a frame in which said blind is mounted at its upper end, said frame including an end block member, a rod member extending from

said block member, and means extending therefrom for rigidly holding said slats in vertical position, said means including a toothed blade pivotally mounted at the end of said rod member and positioned through slots in said slats, and means associated with said blade for fixedly holding the same horizontally extended or at an angle.

8. The combination with window blinds comprising two blinds, each consisting of a plurality of vertically suspended slats having means for turning adjustment about their lateral axis of a frame in which said blinds are mounted at their upper ends, said frame including end block members, rod members extending downwardly from each of said block members, and means extending therefrom for rigidly holding said slats in vertical position or for gathering the lower ends of said slats together to effect a drape appearance.
